(57) **CLAIM**

The ornamental design for a removable ornamentation for eyeglasses, as shown and described.

DESCRIPTION

FIG. 1 is an isometric view of a removable ornamentation for eyeglasses showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design. The broken lines shown in the drawing are included for the purpose of illustrating environmental subject matter and form no part of the claimed design.

1 Claim, 4 Drawing Sheets
